UNITED STATES PATENT OFFICE.

WILLIAM C. SMITH, OF KANSAS CITY, MISSOURI, AND GEORGE H. BARBER, OF OSAWATOMIE, KANSAS.

BOX-CAR.

1,103,697.

Specification of Letters Patent. Patented July 14, 1914.

Application filed June 13, 1913. Serial No. 773,507.

To all whom it may concern:

Be it known that we, WILLIAM C. SMITH and GEORGE H. BARBER, citizens of the United States, residing at Kansas City and 5 Osawatomie, respectively, in the counties of Jackson and Miami, respectively, and States of Missouri and Kansas, respectively, have invented new and useful Improvements in Box-Cars, of which the following 10 is a specification.

The invention relates generally to an improvement in box and other house cars and particularly to a combined siding and lining to be used in the construction of such cars 15 to effectively prevent leakage from within or without, and to provide for relatively adjusting the sections of the siding or lining in the event of shrinkage.

The main object of the present invention 20 is the provision of a siding and a lining each constructed of boards having particularly formed joining edges, with the joints of the lining breaking joint with the joints of the siding, each board of both the siding 25 and the lining being connected to a metal bracing or structure of the sides and ends of the car to provide for maintaining a close joint effect in both the siding and lining under all conditions.

30 The invention in its preferred form of details will be described in the following specification, reference being had particularly to the accompanying drawings, in which:

Figure 1 is a view in elevation of the side 35 of the car constructed in accordance with my invention. Fig. 2 is a vertical central section of the same.

Referring particularly to the accompanying drawings, the improved siding 1 is made 40 up of a series of boards 2 extending longitudinally of the side or end of the car as the case may be, and formed on their meeting edges to present a joint 3 having a portion 4 at right angles to the surface of the 45 siding and a forward portion 5 at a downward and forward inclination to the portion 4. The joint thus provided presents an upwardly inclined surface against the ingress of rain or snow and hence will effectively

50 prevent leakage from without. The lining, which is designed to fit snugly against the inner surface of the siding, is composed of independent board sections 6 corresponding generally in width to the boards of the siding and arranged in the same general direction. The meeting edges of the boards of the lining, however, are formed for 55 tongue and groove junctures 7 and are so arranged with respect to the boards of the siding as to break joint with the latter. The 60 metal bracing or tie bars 8 usual in such structures overlie the siding, and the improved siding and lining are secured to these bars by bolts 9, there being two bolts passed through each board of the siding, 65 which by reason of the similar width of the board of the siding and lining and their break joint relation provides two bolts through each board of the lining.

In the construction described, it will be 70 noted that by reason of the break joint and peculiar construction of the connections leakage is prevented from within or without, while at the same time a comparatively smooth interior surface is presented to avoid 75 injury to the contents of the car.

What is claimed is:

A car wall including a siding and a lining therefor, said siding and lining being each 80 constructed of sections of approximately uniform width, joints of the siding sections being offset with respect to the joints of the lining sections, the lining and siding being 85 in contact throughout their lengths and breadths, the joints between the siding sections presenting an inner portion at right angles to the surface of the siding and an outer portion inclined with respect to said surface, the joints between the lining sections being of the tongue and groove type. 90

In testimony whereof we affix our signatures in presence of two witnesses.

WILLIAM C. SMITH.
GEORGE H. BARBER.
